UNITED STATES PATENT OFFICE.

HOWARD A. THOMPSON, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed August 11, 1926. Serial No. 128,594.

My invention relates to railway traffic controlling apparatus, and particularly to apparatus of the type comprising train carried governing means controlled by energy received from the trackway. More particularly my present invention relates to the trackway portion of such apparatus.

I will describe one form of trackway apparatus embodying my invention, and will then point out the novel features thereof in claims.

In the accompanying drawings Figs. 1 and 2 are diagrammatic views, which when placed end to end with Fig. 1 on the left, illustrate one form of trackway apparatus embodying my invention.

Referring to the drawings, the reference characters 1 and 1^a designate the track rails of a stretch of railway track over which traffic at times moves in both directions. These track rails are divided, by means of insulated joints 2, into a plurality of successive sections, A—B, B—C, C—D, D—E, E—F, F—G, G—H, etc. It will be seen that certain of these track sections, such as A—B, D—E and G—H are comparatively short and that these shorter sections, which I will hereinafter term "reset" sections, divide, the rest of the track into a plurality of blocks each comprising two track sections. The stretch of track therefore comprises alternately disposed blocks and reset sections.

Each section in each of the blocks inter-mediate the reset sections is provided with a track battery designated by the reference character 4 and connected across the rails adjacent one end of the section; and with a track relay designated by the reference character R with a suitable distinguishing exponent connected across the rails adjacent the opposite end of such section. It will be seen, therefore, that each such section is provided with a track circuit including a track battery 4, a track relay R, and the rails of the associated section in series.

Each reset section is also provided with a track circuit but the source of track circuit current for each reset section is a transformer designated by the reference character U with a suitable distinguishing exponent and having its terminals connected from the right-hand end of rail 1 to the left-hand end of rail 1^a of the corresponding section. The

usual impedance 7 is interposed between the secondary 5 of each transformer U and a rail of the corresponding section. Each reset section is further provided with a track relay responsive to alternating current supplied thereto and designated in the drawing by the reference character K with an exponent corresponding to the location. Each relay K has its terminals connected with the left-hand end of rail 1 and the right-hand end of rail 1^a of the corresponding reset section. Referring particularly to section D—E, it will be seen that when alternating current is supplied to primary 6 of transformer U^D, current flows from the secondary 5 of this transformer, through impedance 7 and rail 1 of section D—E to relay K^D and thence through rail 1^a of the section to the left-hand terminal of the transformer U^D. It will be plain from the drawing that current thus supplied to the rails of section D—E flows through the rails of the section in series in such manner that the current flows in the same direction at an instant in both track rails.

Associated with each track relay K is a repeater relay designated by the reference character P with an exponent corresponding to the location. The control of each relay P will be described in detail hereinafter. When relay P^D is de-energized, primary 6 of transformer U^D is supplied with alternating current from secondary 8 of a line transformer T^D, over back contact 79 of relay P^D. The primary 9 of transformer T^D is constantly supplied with alternating current from a suitable source such as an alternator M over line wires 3 and 3^a.

The control of each of the remaining transformers U by an associated repeater relay P is similar to the control of transformer U^D by relay P^D.

Associated with each direct current track relay R is a slow releasing line relay and a stick relay designated by the reference characters J and S, respectively, with exponents corresponding to the location. The line relays and stick relays are at times supplied with energy from batteries each designated by the reference character Q with a suitable distinguishing exponent. Referring particularly to relay J^E, this relay is provided with a circuit which may be traced from battery Q^E, through wires 16, 17 and 18,

- front contact 19 of relay J^H , wires 20 and 21, front contact 22 of relay R^G , wire 23, back contact 24 of relay S^D , wire 25, back contact 26 of relay K^D , wire 27, front contact 28 of relay P^D , wire 29, front contact 30 of relay R^E , wire 31, winding of relay J^E , and common wire 15, back to battery Q^G . Relay J^E is, therefore, energized only when relays J^H , R^G , P^D and R^E are energized and when relays S^D and K^D are de-energized. The circuit just traced is provided with a branch which may be traced from battery Q^G , through wires 16, 32 and 33, front contact 34 of relay S^H , and wire 35 to wire 21. When relay S^H is energized, therefore, to close the circuit through this branch, front contact 19 of relay J^H is eliminated from the control of relay J^E . The circuit for relay J^E is provided with a second branch which passes from wire 25, through front contact 26 of relay K^D , wire 36, and back contact 28 of relay P^D to wire 29. The circuit first traced for relay J^E required relay K^D to be deenergized and relay P^D to be energized. By virtue of the branch just traced, however, a circuit is completed for relay J^E when relay K^D is energized and relay P^D is de-energized.

The circuits for each of the remaining relays J are similar to those just traced for relay J^E and will be understood from the drawing without further explanation.

Relay P^D is provided with a circuit which passes from battery Q^D , through wires 37, 38, 39 and 60, front contact 61 of relay J^D , wire 62, front contact 63 of relay J^E , wire 64, winding of relay P^D and common wire 15 back to battery Q^D . Relay P^D is therefore energized only when both line relays J^D and J^E for the adjacent sections are energized. When either of these relays is open, relay P^D becomes de-energized, thereby closing at back contact 79 thereon the circuit for the primary 6 of transformer U^D and supplying alternating current to the rails of section $D-E$ as explained hereinbefore.

Each of the remaining relays P is controlled by the adjacent relays J in the same manner as just explained in connection with the control of relay P^D by relays J^D and J^E .

The stick relay S^E is provided with a pick-up circuit from battery Q^D , through wires 37, 38 and 39, back contact 40 of relay J^D , wires 41 and 42, back contact 43 of relay R^D , wire 44, back contact 45 of relay K^D , wire 46, back contact 47 of relay P^D , wire 48, front contact 49 of relay R^E , wire 50, front contact 51 of relay J^E , wires 52 and 53, winding of relay S^E , and common wire 15, back to battery Q^D . This pick-up circuit is closed only when relays R^D and J^E are energized and when relays J^D , R^D , K^D and P^D are de-energized. When relay R^E becomes de-energized, the pick-up circuit for

relay S^E is opened, but a stick circuit is then closed for relay S^E from battery Q^D over wires 37, 38, and 54, back contact 55 of relay J^E , wires 56 and 57, front contact 58 of relay S^E , wires 59 and 53, winding of relay S^E , and common wire 15 back to battery Q^D . Having once been energized by the pick-up circuit above traced, the stick relay S^E is subsequently maintained in its energized condition as long as relay J^E remains open. Each of the remaining stick relays S is provided with circuits similar to those just traced for relay S^E .

Means are also provided for supplying each section in each of the blocks of the stretch with alternating train controlling current. For this purpose each such section is provided with two transformers one connected across the rails adjacent each end of the section and each designated by the reference character L with an appropriate distinguishing exponent. At points C and F the secondaries 10 of the transformers L are connected in series with the track batteries 4 on opposite sides of the insulated joints at these points and to distinguish between the two transformers which would otherwise have the same reference character I have added subscripts to the reference characters for these transformers.

Referring particularly to transformer L^E , the primary 11 of this transformer is at times supplied with alternating current from transformer U^D , over a circuit which may be traced from the right-hand terminal 100 of secondary 5 of transformer U^D , through impedance 7, rail 1 of section $D-E$, wires 65, 66 and 67, front contact 68 of relay J^D , wire 69, back contact 70 of relay R^E , wire 71, primary 11 of transformer L^E , wires 72, 73, 74 and 75, rail 1^a of section $D-E$ and back to secondary 5 of transformer U^D . It will therefore be plain that when relay R^E is de-energized and when relay J^D is energized, primary 11 of transformer L^E is supplied with current from transformer U^D in parallel with relay K^D .

Transformers L^A , L^B , L^E , L^G , and L^H are each provided with a circuit similar to that just traced for transformer L^E and the control of these transformers will be apparent from an inspection of the drawing.

When relay J^D is energized and relay R^E is also energized, current flows from secondary 5 of transformer U^D , through rail 1 of section $D-E$, wires 65, 66 and 67, front contact 68 of relay J^D , wire 69, front contact 70 of relay R^E , wire 76, primary 14 of transformer V^E , wires 77, 73, 74 and 75, and rail 1^a of section $D-E$ back to secondary 5 of transformer U^D . When this circuit is closed, therefore, alternating current is supplied to primary 14 of transformer V^E , in parallel with relay K^D from transformer U^D . The secondary 13 of transformer V^E is con-

stantly connected with primary 11 of transformer L^F_2 , over a circuit which may be traced from the right-hand terminal of secondary 13 of transformer V^E , through wire 58, primary 11 of transformer L^F_2 and common wire 15 back to the left-hand terminal of secondary 13 of transformer V^E . The circuits over which alternating current is supplied to transformers L^C_1 , L^C_2 and L^F_1 are similar to the circuits just described for the supply of alternating current to transformer L^F_2 and will be understood from the drawing.

As shown in the drawing, the stretch of track is unoccupied, so that all direct current track relays R are energized and all line relays J are also energized, whereas all stick relays S are de-energized. Each of the repeater relays P is therefore energized and the primary circuit for each transformer 20 U is interrupted. The supply of current to the rails of each of the reset sections is therefore interrupted and relays K are all de-energized. The supply of alternating current to the rails of all sections is therefore discontinued.

Before explaining the operation of the apparatus as a whole it should be pointed out that the trackway apparatus herein shown and described is suitable for co-operation with train carried governing means requiring the supply of alternating current to at least one of the track rails to prevent an automatic application of the brakes. If the supply of such current is discontinued, an automatic brake application results unless the engineman takes proper steps to acknowledge the change in traffic conditions. If he does acknowledge, the train may proceed without incurring an application of the brakes. If alternating current is again supplied to the rails occupied by the train and this current is subsequently discontinued, the engineman must again acknowledge to prevent an automatic application of the brakes. One form of train carried governing means suitable for co-operation with the trackway apparatus here disclosed is shown and described in Letters Patent of the United States, No. 1,492,719, issued May 6, 50 1924, to Ronald A. McCann, for railway traffic controlling apparatus.

In apparatus of the type described, the train carried governing means is usually controlled by the alternating current in the trackway through the medium of an inductive receiver carried on the train in advance of the forward axle of the train. With apparatus constructed in this manner it is necessary for the alternating train controlling current to flow through a track rail in advance of the train.

I will now proceed to explain the operation of the apparatus as an eastbound train moves through the stretch of track shown 65 in the drawing. As this train approaches

point A it opens relay R^A , and this causes relay J^A to become de-energized. Relay J^D is therefore de-energized, and relay J^G is also de-energized. Relays P^A , P^D and P^G are therefore de-energized, the circuit for each of these relays being open at a front contact of one of line relays J associated therewith. The primary 6 of each transformer U is therefore supplied with alternating current so that current is supplied to the rails of each of the reset sections A—B, D—E and G—H. Relays K are therefore all energized. With all relays K energized and relays P de-energized, each of the relays J^B , J^E , and J^H is energized, one branch for the circuit of each such relay being closed over a front contact of the associated relay K and a back contact of the corresponding relay P . Since relay J^A is de-energized no current is supplied to the primary 14 of transformer V^B and transformers V^E and V^H are also de-energized. Relay J^B is energized, however, and transformer V^A is also energized. Transformers V^D and V^G are also supplied with alternating current and current is therefore supplied to primaries 11 of transformers L^C_1 and L^F_1 . Each of the remaining transformers L is de-energized.

When the eastbound train is in the section to the left of point A, so that relay R^A is de-energized, a circuit for the primary 11 of transformer L^A is closed at back contact 80 of relay R^A . Alternating current is therefore supplied to the rails of the section to the left of point A so that the train receives alternating current from a point in advance of the train and an automatic application of the brakes is prevented.

When the train enters reset section A—B, relay K^A becomes de-energized, thereby completing a pick-up circuit for relay S^B , so that this relay closes its front contact 58. The dropping of relay K^A also interrupts the circuit for relay J^B so that this relay opens 105 its front contact. The pick-up circuit for relay S^B is therefore opened at front contact 51 of relay J^B , but relay S^B is now maintained in its energized condition over back contact 55 of relay J^B . As the train proceeds through section A—B, alternating current from transformer U^A flows from the right-hand terminal of secondary 5 of this transformer, through impedance 7 to rail 1 of section A—B, down this rail to the forward wheels and axles of the train and thence through rail 1^a back to the left-hand terminal of secondary 5 of transformer U^A . Current supplied over the path just traced to rail 1 operates the train carried governing means through the receiving apparatus on the train to prevent an automatic application of the brakes.

When the train enters section B—C, relay R^B becomes de-energized but in other re-

spects the apparatus is unaffected. As has already been explained, primary 11 of transformer L^c_1 is being supplied with alternating current from transformer V^D , so that 5 the train receives alternating current from transformer L^c_1 as it proceeds through section B—C. When the train enters section C—D, relay R^D becomes de-energized and current is then supplied to primary 11 of 10 transformer L^D over back contact 80 of relay R^D . The train therefore receives alternating current from transformer L^D as it proceeds through section C—D and an automatic application of the brakes on board the 15 train is prevented. The operation of the apparatus as the train continues its progress through the remaining sections illustrated in the drawing will be understood without further explanation.

20 The operation of the apparatus when a westbound train proceeds through the stretch of track shown in the drawing is similar to the operation when the stretch is traversed by an eastbound train and will be readily 25 understood by one skilled in the art. It should be noted, however, that when a westbound train occupies one of the reset sections, such as D—E, current from the transformer U^D flows from the right-hand terminal of secondary 5 of this transformer, through rail 1 of the section to the wheels and axles of a train and thence to rail 1^a in advance of the train, back to the left-hand terminal of secondary 5 of transformer U^D . 30 The alternating current in rail 1 in advance of the train serves to actuate the train carried governing means through the medium of a receiver and an automatic application of the brakes is therefore prevented. When 35 the train occupies one of the sections comprising the blocks between adjacent reset sections it must be supplied with alternating current from one of the transformers L located adjacent the left-hand end of the section. The selection and control of the supply circuit for the transformers L for accomplishing this result will be plain from the explanation of the operation for movements of eastbound traffic.

40 I will next assume that a westbound train occupies the stretch of track shown in the drawing, as for example the section to the right of point H. All opposing line relays in advance of this train, that is, line relays 45 J^B , J^E , and J^H , are de-energized. I will also assume that under these conditions an eastbound train proceeds through the stretch. The eastbound train will receive alternating current from transformer U^A as it proceeds 50 through section A—B, but since relay J^E is open, the primary circuits for transformers V^D and L^D are open at front contact 81 of relay J^E . Neither section B—C nor C—D is supplied with train controlling current in 55 advance of the train, therefore, and when

the eastbound train passes point B the engineman must acknowledge to prevent an application of the brakes. When the train enters the reset section D—E it is again supplied with alternating train controlling current and is subsequently deprived of such current as the train passes point E because transformer L^F_1 is de-energized, primary circuit for transformer V^G being open at front contact 81 of relay J^H . It is manifest therefore that when the stretch is occupied by a train moving in one direction, the engineman of a second train approaching from the other direction must acknowledge to prevent a brake application as such second train leaves each reset section.

It should also be pointed out that if a train moving in either direction occupies one block, the supply of train controlling current to the block in rear is interrupted. For 85 example, I will assume that an eastbound train occupies section E—F so that relay J^E is de-energized. Transformers L^c_1 and L^D are therefore de-energized and a following train will incur an application of the brakes 90 at point B when the engineman acknowledges. When this following train enters section D—E, current from transformer U^D actuates the train carried governing means so that when the train leaves the reset section 95 the engineman must again acknowledge to prevent an application of the brakes.

Similarly, if the forward train occupies section F—G, relay J^E is still de-energized, and the following train will incur automatic 100 applications at points B and E unless the engineman acknowledges.

Although I have herein shown and described only one form of apparatus embodying my invention, it is understood that various changes and modifications may be made therein within the scope of the appended claims without departing from the spirit and scope of my invention.

Having thus described my invention, what 110 I claim is:

1. In combination with a section of railway track, a relay having its terminals connected with one end of one rail and with the other end of the other rail, respectively 115 and a source of energy having its terminals connected with the free ends of such rails, respectively.

2. In combination, two adjacent sections of railway track, a source of alternating electromotive force connected with opposite ends of the two rails of one section, and a transformer having its primary connected with the free ends of the rails of such one section, respectively, and having its secondary connected with the rails of the other section.

3. In combination, two adjacent sections of railway track, a source of alternating electromotive force connected with the op-

posite ends of the two rails of one section, a transformer having its primary connected with the free ends of the rails of such one section, respectively, and means for supplying 5 alternating current from the secondary of such transformer to the rails of the other section.

4. In combination a stretch of railway track comprising a plurality of alternate blocks and reset sections, means controlled by traffic conditions for at times supplying current to the rails of each block, and means for at times connecting a source of current with one end of one rail and the opposite 15 end of the other rail of each such reset section.

5. In combination; a stretch of railway track comprising a right-hand, a left-hand, and an intermediate section; two track circuits, one for the right-hand section and 20 one for the left-hand section and each comprising a track relay, a source of current and the rails of the section in series; two line relays one controlled by each track relay, a repeater relay controlled by said two line relays, and means controlled by said repeater relay for at times supplying current 25 to the rails of the intermediate section in series in such manner that the current flows through both rails in the same direction.

6. In combination, a section of railway track, a source of energy having its terminals connected with one end of one rail and the opposite end of the other rail, respectively, a relay having its terminals connected with the free ends of such rails, and traffic governing means controlled by said 35 relay.

7. In combination, a stretch of railway track divided into alternately disposed blocks and reset sections, a track relay for 40

each block, a line relay for each block controlled by the associated track relay and by the line relay for the block next in advance, and means controlled by each line relay for 45 at times separately supplying train controlling current to the rails of the reset section and the block next in rear.

8. In combination, a stretch of railway track divided into alternately disposed blocks and reset sections, a track relay for 50 each block, a line relay for each block controlled by the associated track relay and by the line relay for the block next in advance, a repeater relay for each reset section arranged 55 to be de-energized when an adjacent line relay is open, and means controlled by each repeater relay for at times supplying the associated reset section with train controlling current which flows through the 60 rails of the section in series in the same direction.

9. In combination, a stretch of railway track divided into alternately disposed blocks and reset sections, a repeater relay 65 for each section, a track relay having its terminals connected with one end of one rail and the other end of the other rail, respectively, of each reset section, means controlled by each repeater relay for supplying alternating 70 train controlling current to the free ends of the rails of the associated section, a line relay for each block controlled by the line relay for the block next in advance and by the track relay and repeater relay for 75 the reset section next in advance, and means controlled by each line relay for supplying alternating train controlling current to the rails of the block next in rear.

In testimony whereof I affix my signature.

HOWARD A. THOMPSON.
